COUNTER DISPLAY BINDER

John C. Burkhardt, Detroit, Mich., assignor to
The Burkhardt Company, Detroit, Mich., a cor-
poration of Michigan

Application February 6, 1933, Serial No. 655,377

5 Claims. (Cl. 129—1)

The present invention pertains to a novel sample display binder intended to be set on a store counter in such a manner that the leaves swing on a horizontal axis. The leaves may 5 carry photographs or printed matter relative to the merchandise on sale or may in themselves be samples of merchandise such as paper or cloth.

One of the principal objects of the invention is to provide a simple and inexpensive device of 10 this character that may be collapsed into a flat condition for packing and shipping. Moreover, it is an object of the invention to form the binder cover of a single continuous strip of cover material with binding posts at its ends. The cover material is formed with at least two transverse hinges 15 so that it forms a triangle having a base adapted to be set on the counter and having the sheets bound at the apex or the edge opposite the base. In the preferred embodiment of the invention, 20 one of the ends of the cover is detachably fastened to the binding posts and may be readily separated therefrom without releasing the bound sheets. This arrangement permits collapsing the device into a flat and compact condition for 25 packing, carrying or shipping. In this connection, another object of the invention is to provide a combined binding post and detachable fastener adapted to function in the manner set forth above.

30 The invention further provides a display binder which may be collapsed into a flat condition without separating the binding edges. This is accomplished by scoring the cover across the base of the triangle and permits the use of a standard Chicago screw post.

The invention is fully disclosed by way of example in the following description and in the accompanying drawings in which

Figure 1 is a perspective view of the device in 40 operative position;

Figure 2 is a detail vertical section thereof showing the novel binding post;

Figure 3 is an elevation thereof in collapsed condition;

Figure 4 is a perspective view of a modified form in operative position;

Figure 5 is a detail vertical section thereof showing the binding post;

Figure 6 is a detail elevation thereof in collapsed condition;

Figure 7 is a detail vertical section of a modified construction showing this binding arrangement; and

Figure 8 is an elevation of the same form in 55 collapsed condition.

Reference to these views will now be made by use of like characters which are employed to designate corresponding parts throughout.

In Figures 1 to 3 is shown an elongated piece 5 of suitable stiff covering material which is formed with two hinges 1 and 2 which divide the cover into a base or bottom section 3 and two sides 4 and 5. The hinges may be formed in any suitable way as by scoring the material and reinforcing with tape, or by providing the parts 10 3, 4 and 5 as separate pieces and uniting them with tape or other hinging means. The sides 4 and 5 are preferably scored again transversely at 6 and 7 near the ends of the cover to form binding strips 8 and 9.

Sheets 10 are bound to one of the strips by means of binding posts, one of which is shown in detail in Figure 2. Each post comprises a tapped member 11 passed through holes in the sheets and receiving a screw member 12 passed through 15 the strip 8 and formed with a screwhead 13. The free end of the member 11 has a flange 14 which bears against the adjacent sheet to clamp the sheets against the strip 8 on tightening the 20 screw 12.

The other strip 9 carries a glove snap fastener adapted to attach on the inner end of the binding post 11—14. Each such fastener comprises a rivet eye 15 passed through the strip 9 and carrying a head or button 16 on its outer end. The inner end of the corresponding member 11 is formed with an annular groove 17, and the inner end of the rivet 15 carries a cup 18 with an inwardly beaded edge 19 containing a spring wire 25 30 35 40 45 50 55 adapted to snap into the groove 17. By means of this device, the edge 9 is detachably fastened to the posts 11—14 when the device is in the operative position shown in Figure 1. It will be evident that the merchandise depicted on the sheets 10 may be displayed by merely turning the sheets one at a time.

The device is collapsed for packing and transportation, as in Figure 3, by releasing the snap fasteners 15—20 from the posts 11—14 and bringing the sides 3 and 5 into one plane. The cover is folded at the hinges to bring the side 4 and the set of sheets over the sides 3 and 5.

The embodiment shown in Figures 4, 5 and 6 comprises a cover which is similarly hinged or scored to form three sides 21, 22 and 23 with the 50 free ends opposite the base 22 and sheets 24 fastened between these ends. In this case, however, ordinary Chicago screw posts are employed, embodying each a tapped member 25 receiving 55 a screw 26 as shown in Figure 5. This type of

fastener does not permit detachment without releasing the sheets.

The base 22 is scored transversely at 27 so that the sides 21 and 23 may be brought towards each other by folding the base inwardly or outwardly along the scoring 27. This operation flattens the cover for shipping purposes. The sheets 24 may be folded back over the cover as in Figure 6 or may be swung in the other direction to extend straight outwardly from the cover and thereby avoid the bulge 28.

In Figures 7 and 8 is shown still another construction comprising a continuous cover having sides 30 and 31 and a base 32 scored transversely along its center line as indicated by the numeral 33. It will be evident that the cover may be erected in the same manner as that shown in Figure 4. The binding strips 34 and 35 at the ends of the cover are turned inwardly of the triangle as shown in Figure 7. The sheets 36 are attached thereto by detachable fasteners of the type described in detail with reference to Figure 2 and here indicated generally as comprising a binding post 37 and a detachable snap fastener 38. In dismantling this device for packing and transportation, the fasteners 38 are first released from the posts 37, and the strips 34 and 35 are swung into the planes of the sides 30 and 31 respectively. This brings the sheets 36 against the outer surface of the side 31 with reference to Figure 7. The side 30 is then swung around the free ends of the sheets, thereby enclosing the sheets and bringing the fasteners 38 into position for re-attachment to the posts 37 shown in Figure 8. The re-attachment is made and the base 32 is flattened by folding on its scored line 33. The base may be folded to extend outwardly from the sides 30 and 31 or inwardly to extend between the sides as shown in Figure 8, in which case the sheets 36 are preferably divided at opposite sides of the folded base.

Although specific embodiments of the invention have been illustrated and described, it will be understood that various alterations in the details of construction may be made without departing from the scope of the invention as indicated by the appended claims.

What I claim is:

1. A display binder comprising a bottom section, a side section hinged to each end of said bottom section, said side sections being stiff,

whereby the sections may be formed into a triangular figure with said bottom section as a base and the free ends of said side sections in juxtaposition opposite said bottom section, and means for holding said free ends together and binding a plurality of sheets therebetween. 5

2. A display binder comprising a bottom section, a side section of stiff material hinged to each end of said bottom section, said side sections being stiff, whereby the sections may be formed into a triangular figure with said bottom section as a base and the free ends of said side sections in juxtaposition opposite said bottom section, and means for holding said free ends together and binding a plurality of sheets there- 10 between, said bottom section having a fold line parallel to said ends, whereby said bottom section is adapted to fold between and parallel to its ends.

3. A display binder comprising a bottom section, a side section hinged to each end of said bottom section, said side sections being stiff, whereby the sections may be formed into a triangular figure with said bottom section as a base and the free ends of said side sections in juxtaposition opposite said bottom section, binding 25 means carried by one of said free ends, and fastening means carried by the other free end and adapted to be detachably attached to said binding means.

4. A display binder comprising a cover of stiff 30 material folded along two transverse lines to form a three-sided figure with the ends of the cover disposed at one of the vertices of said figure, said ends being turned inwardly of said figure, binding means carried by one of said ends and 35 adapted to secure a plurality of sheets thereto, and complementary snap fastener elements carried respectively by said binding means and the other end of said cover.

5. A display binder comprising a cover of stiff 40 material folded along two transverse lines to form a three-sided figure with the ends of the cover disposed at one of the vertices of said figure, said ends being turned inwardly of said figure, binding means carried by one of said ends and 45 adapted to secure a plurality of sheets thereto, and complementary snap fastener elements carried respectively by said means and the other end of said cover, said cover being scored between and parallel to said lines. 50

JOHN C. BURKHARDT.
